DESIGN FOR A MINIATURE LOG CABIN ASH RECEPTACLE

Jerry M. Surkin and Marvin E. Herpe,
Chicago, Ill.

Application March 29, 1948, Serial No. 145,408

Term of patent 3½ years

(Cl. D85—2)

To all whom it may concern:

Be it known that we, Jerry M. Surkin and Marvin E. Herpe, both citizens of the United States of America, and both residing at Chicago, in the county of Cook and State of Illinois, have invented a new, original, and ornamental Design for a Miniature Log Cabin Ash Receptacle, of which the following is a specification, reference being had to the accompanying drawing, forming part thereof.

Figure 1 is a perspective view of a miniature log cabin ash receptacle, showing our new design.

Fig. 2 is a front view thereof.

Fig. 3 is a rear view thereof.

Fig. 4 is a top plan view thereof.

Figs. 5 and 6 are end views thereof.

We claim:

The ornamental design for a miniature log cabin ash receptacle, as shown.

JERRY M. SURKIN.
MARVIN E. HERPE.
